(57) **CLAIM**

The ornamental design for an industrial robot as shown and described.

DESCRIPTION

FIG. 1 is a front view of an industrial robot of the present invention;

FIG. 2 is a back view thereof;

FIG. 3 is a top plan view thereof;

FIG. 4 is a bottom view thereof;

FIG. 5 is a right side view thereof;

FIG. 6 is a left side view thereof;

FIG. 7 is a front, top and left side perspective view thereof;

FIG. 8 is a back, top and left side perspective view thereof;

FIG. 9 is a back, top and right side perspective view thereof; and,

FIG. 10 is a front, top and right side perspective view thereof.

1 Claim, 10 Drawing Sheets
